UNITED STATES PATENT OFFICE

KINGSLEY VAN A. GWYER, OF STRATFORD, CONNECTICUT

COLLAPSIBLE SUPPORT

Application filed October 17, 1929. Serial No. 400,279.

This invention relates to a support which may be used as a camp grate, a supporting shelf for use in a refrigerator, a grate or grid for portable oil and gasoline stoves and the like and has for an object to provide such a support made of two or more quickly and easily separable individual sections or individual gridirons, so that the support may be packed in a small space for carriage and storage, or to facilitate mounting and demounting as in case of use in a refrigerator.

It is a further object of this invention to provide a collapsible support which can be quickly assembled and in which the sections or gridirons when assembled will remain in the same plane.

With the foregoing and other objects in view as will become apparent, this invention consists of the constructions, arrangements and combinations of parts set forth, disclosed and claimed in the following specification considered in connection with the accompanying drawings.

In these drawings:

Fig. 1 is a top plan view of an embodiment of this invention showing the support in extended position.

Fig. 2 is a side plan view of the support as placed in position over a camp fire and supported by a brickwork such as is often placed in camping parks.

Fig. 3 is a section on line 3-3 of Fig. 1.

Fig. 4 is a section on line 4-4 of Fig. 1.

Fig. 5 is a fragmentary top plan view of another embodiment of this invention.

Fig. 6 is a section on line 6-6 of Fig. 5, and

Fig. 7 indicates how the support is used for the removable shelves of a refrigerator.

There is shown at 10 a support embodying this invention. As shown, the support comprises three sections or gridirons, a central section or gridiron 11 and two wing sections or gridirons 12 and 13.

The central section comprises a rectangular frame 14 to the top of which are affixed a plurality of transverse bars 15, the bars 15 being affixed to the frame by any appropriate means, preferably by spot welding as at 16. Near one end of the section 11 a transverse

bar 17 is folded about the frame 14 so as to lie under the frame 14 and bars 15 and the folded over ends 18 of bar 17 are affixed to the top of frame 14 likewise by spot welding. Another similar bar 19 may be affixed to the other end of section 11, and these bars 17 and 19 serve as holding bars, and assist in keeping the wing sections 12 and 13 in place, as will become apparent.

Both wing sections 12 and 13 being identical in construction, only one need be described in detail. Each wing comprises a substantially rectangular frame 20 likewise having bars 15 spot welded thereto as at 16. One end of frame 20 is slightly narrowed or reduced in width as at 21, and this narrowed end curved downwardly and bent into a substantially S-shaped hook as shown, having the inner loop 22 adapted to be curved or hooked under the transverse end 24 of frame 14, while the outer loop 23 of the S is adapted to be hooked or curved over the holding bars 17 or 19.

In operation, the loop 23 is inserted at an angle in the space between the bar 17 and the transverse end 24 of the central section, and beneath bars 15, and then the wing 12 is swung about or upwardly if the central section is horizontal until it is in the same plane with the central section 11, whereupon loop 23 will hook over bar 17 while loop 22 will receive, hook or curve under the transverse end 24 preventing further rotation, the other wing or additional section being similarly attached. The assembled support 10 may then be supported at each end 25 and 26 by any convenient supporting means, such as a pair of forked sticks or rods or pile of rocks, logs or bricks 27 as shown, if used as a camp grate such brick supports being often prepared in camping parks. A fire 28 is then built under the support 10, and the support may then be used to support pots and pans over the fire for cooking purposes, or food for broiling as desired. If used in other positions as for example in a refrigerator 31 as illustrated in Fig. 7, the ends of the sections merely rest on or are supported by the usual shelf supports 30. To disassemble the support, it needs only be removed and each wing may

be swung downwardly until the hooks separate from the central section and then the separated sections may be packed on top of each other for storage or carriage purposes.

- 5 When used for such uses as the shelves for a refrigerator, the support will ordinarily comprise only two sections. In refrigerators, if the shelves are in one piece it is often difficult to mount or remove the shelves. With this 10 sectional support, however, it is a very simple matter to either mount or remove the shelves or supports as will be obvious.

The embodiment shown in Figs. 5 and 6 is identical with that shown in the other embodiment save that the wings have been strengthened by having a transverse end 29 connect the ends of its outer loops 23' on its frame 20', thus making the frame 20' a closed frame as contrasted with the open frame 20.

- 20 Although the support 10 has been described in connection with Figs. 1 and 2 as comprising three gridirons or sections, it will be apparent that it may be composed of only two sections by omitting one of the wings or more 25 than two sections by merely providing extra wing sections and by adding a holding bar 17 and 19 to the extra wing sections near their outer ends and interposing such extra wing sections between the central section and the 30 outer wings. It will also be noted that when assembled the sections are all in the same plane giving a flat top support. Further, the weight of the sections and any articles thereon clamp the sections firmly together so 35 there is no danger of their becoming accidentally detached in use. The end cross bars 24 of the central section seat in the recess formed by the loop 22 so the sections cannot slide longitudinally of each other, and the hook 40 23 engaging over bar 17 will prevent their separating. They may, however, be easily separated when desired by dropping down the end section until recess formed by loop 22 is removed from bar 24 when hook 23 can 45 be lifted from bar 17.

Having thus set forth and disclosed the nature of this invention, what is claimed is:

1. A collapsible support comprising a plurality of sections, each section comprising a 50 frame and a plurality of bars affixed thereto; one of said sections having a hooked end adapted to be curved under a transverse end and over a bar of another section to detachably secure said sections together in a substantially common plane.

2. A collapsible support comprising a plurality of sections, each section comprising a frame and a plurality of bars affixed thereto, the frame of one of said sections being recessed adjacent one projecting end, said projecting end being adapted to be held over a bar of another of said sections when the recessed portion of the frame of the former section is curved under a transverse end of 60 the latter section to thereby detachably se-

cure said sections in a substantially common plane.

3. A support comprising a plurality of sections, each section comprising a frame and a plurality of grate bars affixed thereto, one of said sections having a holding bar affixed thereto adjacent one end thereof, another of said sections having a recess formed in its frame adjacent one end thereto, the end of the latter section being adapted to be held over the holding bars of the former section when the recess in its frame is curved under the end of the frame of said former section.

4. A collapsible support comprising a plurality of sections, each of said sections comprising a frame and a plurality of bars, a holding bar affixed to one of said sections adjacent a transverse end thereof, another of said sections having a hooked end adapted to be curved under said transverse end and over a said holding bar to detachably secure said sections together in a substantially common plane.

5. A support comprising a central section and a plurality of wing sections, each section comprising a frame and a plurality of bars affixed thereto, each wing having a hooked end, each wing being adapted to be secured to the central section in a substantially common plane by having its hooked end curved under a transverse end of the central section and over a bar thereof.

6. A support comprising a central section having a frame and bars affixed thereto, a holding bar adjacent each end of the frame and affixed thereto, and a pair of wing sections detachably affixed thereto, the frame of each wing having a hooked end, said hooked end being curved under the transverse end of the central section and over the holding bar to hingedly secure the wings thereto in a substantially common plane.

7. A collapsible support comprising a plurality of substantially rectangular sections, each section comprising a frame and a plurality of grate bars affixed to the top thereof, the frame of the central section having a holding bar adjacent each transverse end and affixed to pass under the frame, the other sections each having the opposite sides of its frame narrowed and formed into a hook at one end, said narrowed hooked end adapted to be curved under the transverse end and over the holding bar of the central section to detachably secure said sections in a substantially common plane.

8. A collapsible and detachable support comprising a plurality of sections, each section comprising a frame and a plurality of bars affixed to said frame, the frame of the central sections having a holding bar secured thereto passing thereunder at each end, the other sections each having one side of its frame at one end narrowed, said narrowed sides being substantially S shaped in trans-

verse view, the inner loop of the **S** being adapted to be curved under the central section frame, and the inner loop of the **S** being adapted to be hooked over the holding bar of the central frame.

9. A collapsible and detachable support comprising a plurality of sections, each section comprising a frame and a plurality of grate bars affixed to said frame, the frame of the central sections having a holding bar secured thereto passing thereunder at each end, the other sections each having one side of its frame at one end narrowed, said narrowed side being substantially **S** shaped in transverse view, the inner loop of the **S** being adapted to be curved under the central section frame, and the inner loop of the **S** being adapted to be hooked over the holding bar of the central frame, the ends of the outer loop of the **S** of each of the other sections having a connecting bar to close the frame.

10. In a sectional support, a pair of grate sections each having a frame and cross bars connecting the sides thereof, the side members of the frame of one of said sections having hooks to engage over a cross bar of the other grate section and having recesses in the tops thereof to receive one end bar of the second section.

In testimony whereof I affix my signature.
KINGSLEY VAN A. GWYER.
